UNITED STATES PATENT OFFICE.

ANDREW J. CONWAY, OF SALINA, OHIO, ASSIGNOR TO HIMSELF AND
EDGAR MICHAEL, OF SAME PLACE.

IMPROVEMENT IN SPIKE-DRAWERS.

Specification forming part of Letters Patent No. 179,272, dated June 27, 1876; application filed
March 13, 1876.

To all whom it may concern:

Be it known that I, ANDREW J. CONWAY, of Salina, Athens county, Ohio, have invented an Improvement in Spike-Drawers, of which the following is a specification:

My invention consists of a griping-tongs suspended from a toothed bar, which gears with a toothed segment of a lever pivoted to a stand, on which is a guideway for the toothed bar, all so arranged that the gripe of the tongs on the spike is increased as the power applied to the lever increases, and a powerful spike-drawer is produced.

Figure 1 is a sectional elevation of my improved spike-drawer, and Fig. 2 is a front elevation.

Similar letters of reference indicate corresponding parts.

A represents the jaws of the griping-tongs, which are connected, by links B, with the vertically-sliding toothed bar C, arranged to slide

up and down in the guideway D of the stand E, and having teeth F on one side, which gear with the toothed segment G of the hand-lever H, pivoted to the stand at I, so that by pressing the lever down the tongs will be forced up with great power for pulling spikes.

The segment I is eccentric, and the toothed part of slide C corresponds in such arrangement that the leverage is most powerful at starting, and the motion increases as the spike draws out and the resistance decreases.

Having thus described my invention, I claim as new and desire to secure by Letters Patent—

The griping-tongs A, toothed slide C, segment lever H G, and stand E, substantially as specified.

ANDREW J. CONWAY.
